WAVE TRANSLATING CIRCUITS

Malcolm Frank Wintle, London, England, assignor to International Standard Electric Corporation, New York, N. Y., a corporation of Delaware

Application May 20, 1947, Serial No. 749,327
In Great Britain July 6, 1946

5 Claims. (Cl. 250—27)

1

The present invention relates to electric wave translating circuits employing thermionic valves.

The principal object of the invention is to provide a thermionic valve circuit which can be used for aperiodic frequency doubling without the necessity for employing any frequency-dependent auxiliary devices such as tuned circuits or filters. The circuit can therefore be used for frequency doubling over a wide range of frequencies without any modification.

This object is achieved according to the invention by providing an electric wave translating circuit comprising a thermionic valve having an anode, a cathode, a control electrode, an anode resistance, a cathode negative feedback resistance, means for applying a signal voltage to the said control electrode, and means for deriving an output voltage from the said anode, in which the said resistances are of such values that the curve of instantaneous anode voltage versus instantaneous control electrode voltage has a substantially constant negative slope over the lower half of the working range, and a substantially constant positive slope over the remainder of the working range.

As will be pointed out later, the circuit arrangement according to the invention has other useful applications besides frequency doubling.

The invention will be described with reference to the accompanying drawing in which—

Fig. 1 shows a simplified basic schematic of a thermionic valve circuit used to explain the principles of the invention;

Fig. 2 shows characteristic curves obtained with the circuit of Fig. 1;

Fig. 3 shows one example of a practical circuit according to the invention; and

Fig. 4 shows two doubling stages in tandem illustrating two methods of coupling such stages together.

In the experimental circuit shown in Fig. 1, a valve 1 has its anode connected to the positive high tension terminal 2 through a high resistance 3 of value R_1 , and its cathode to the negative high tension terminal 4 through a high resistance 5 of value R_2 . Let V_g be the steady voltage applied between the control grid and terminal 4, and let V_a be the corresponding voltage measured between the anode and terminal 4.

The resistances R_1 and R_2 should both be large compared with the reciprocal of the mutual conductance of the valve. They might, for example have values between 0.1 and 1.0 megohm.

When applied the voltage V_g is zero, the anode current will be limited to a small value by the re-

sistances R_1 and R_2 , and the valve will be biased nearly to the cut-off point by the potential drop of the anode current flowing in R_2 , and under this condition the control grid is negative to the cathode, and there is no grid current.

As the applied voltage V_g increases positively from zero, a large negative feedback is provided by the resistance R_2 in series with the cathode, and the negative potential difference between the control grid and the cathode decreases at a much slower rate, on account of the negative feedback. The anode voltage at the same time falls continuously owing to the increase in the anode current. When the control-grid-cathode potential difference reaches zero, the potential difference between the anode and cathode will be very low, possibly a few volts, because R_1 and R_2 will both be large compared with the anode-cathode impedance of the valve in this condition, so that they will absorb the major proportion of the applied high tension voltage.

At or just before the potential difference between the control-grid and the cathode has reached zero, grid current will begin to flow. When this occurs the control-grid-cathode impedance becomes comparable with or smaller than R_2 so that practically the whole of any further signal voltage increases now occur across R_2 . There must therefore be corresponding reductions in the voltage drop across R_1 , so that the anode voltage now rises again as the signal voltage is increased.

Fig. 2 gives characteristic curves showing the relation found between V_g and V_a in the arrangement of Fig. 1, in which the valve employed is the EF50 type pentode, with the screen grid and suppressor grid connected to the anode. The resistances R_1 and R_2 both had the same value 370,000 ohms. The curves A, B and C represent the characteristics obtained when the high tension operating voltage had the values 100 volts, 200 volts and 300 volts, respectively. All the curves are similar in shape and comprise two practically straight inclined portions with opposite slopes, connected by a comparatively sharp curve. The slopes of the two straight portions of the curve are related by the equation $\tan \theta / \tan \varphi = R_1 / R_2$. Thus when $R_1 = R_2$ the two slopes are equal and when R_1 and R_2 are both equal and large compared with the internal impedance of the valve, then θ and φ are nearly 45°.

It has been found that the characteristic curves are substantially parabolic in the immediate neighbourhood of the curved portion. Thus if

the control grid be biased so that the anode voltage has the minimum value M , and a small alternating voltage $e \sin \omega t$ be applied to the control grid, the anode voltage will be given by $ke^2 \sin^2 \omega t = \frac{1}{2}ke^2(1 - \cos 2\omega t)$, where k is a constant. Thus a double frequency component will be obtained from the anode, accompanied by a direct current component $\frac{1}{2}ke^2$, which can be removed by a blocking condenser, or by a transformer. The action of the circuit is independent of the value of ω . If e is not small, the double frequency component will still be obtained but it will be accompanied by other multiple frequency components of small amplitude.

It will be noted that since the slopes of the characteristic curve are practically 45° , the bias value corresponding to the minimum point M will be nearly equal to $E/2$, where E is the voltage of the high tension source. In practice the proper bias voltage is slightly less than $E/2$.

If with this same bias, a train of short unidirectional voltage pulses be applied to the control grid, it will be seen that corresponding output pulses will be obtained which will always be positive pulses, whether the input pulses are positive or negative. Moreover, if the amplitude of the input pulses is large, the output pulses will be of nearly the same amplitude. Thus if a train of mixed positive and negative pulses be applied, all the negative pulses will be inverted, and the output train will consist of all positive pulses.

If the bias be adjusted so that the working point comes on the negative sloping portion of the curve, then the valve operates as an ordinary amplifier with a gain ratio of substantially unity, and a phase change of 180° . If the bias is adjusted so that the working point comes on the positive slope, the same results will be obtained except that there will be no phase change. Hence by providing simple means for changing the value of the bias voltage, the phase of a signal wave may be reversed when desired. This facility, and that mentioned above by which positive output pulses can be obtained from pulses of either sign will be useful, for example, in synchronising time bases for cathode ray tubes.

Referring again to Fig. 2, it will be evident that since the anode voltage is always equal to the applied high tension voltage E less the potential drop produced by the anode current in the resistance R_1 , the curves relating the anode current to the applied voltage V_g will be similar to the curves A, B, C, but inverted, so that the point corresponding to M will be a maximum instead of a minimum. It follows that if a relay (not shown) be connected to series with R_1 , it could be designed or adjusted to operate only for currents exceeding a given value, and then the relay could only be operated by the application of input voltages V_g within a certain relatively narrow range, centered about the value corresponding to the point M .

Fig. 3 shows a practical frequency doubling circuit arrangement according to the invention which includes all the elements shown in Fig. 1. The control grid of the valve is connected through the secondary winding of a transformer 6 to the junction point of two resistances 7 and 8 of valves R_3 and R_4 connected in series between terminals 4 and 5. The high resistances R_1 and R_2 should be equal. The waves whose frequency is to be doubled are applied to input terminals 9 and 10 connected to the primary winding of the transformer 6. The output double frequency waves are obtained from a terminal 11 connected

through a blocking condenser 12 to the anode of the valve 1.

The resistances R_3 and R_4 provide the bias for the control grid of the valve, and should be sufficiently small compared with R_1 and R_2 so that the bias potential is not appreciably affected by the grid current. If E is the potential of the high tension source, then the bias produced by R_3 and R_4 is $R_4 E / (R_3 + R_4)$ and should be adjusted to the value corresponding to the minimum point M of the curve shown in Fig. 2, which applies to the value of E used. As already explained this value will be slightly less than $E/2$. Then in accordance with the explanations already given, the desired double frequency waves free from the direct current component will be obtained from terminal 11.

The secondary winding of the transformer 6 should present a low impedance to the grid current for reasons already explained.

It will be evident also that if trains of short unidirectional pulses are applied to the control grid of the valve 1 through the transformer 6 (or in any other conventional way), the output pulses obtained at terminal 11 will always be positive pulses, irrespective of whether the input pulses are positive or negative.

Furthermore, by making the resistances R_3 and R_4 adjustable, the operating point may be placed on the straight part of the Fig. 2 characteristic either on the positive or on the negative slope, as desired, and then normal amplification will be obtained without appreciable distortion.

A phase change of 180° will be obtained if the negative slope is used, but none with the positive slope.

Fig. 4 shows two stages of frequency doubling and illustrates two other methods of coupling the doubling circuit to a proceeding stage.

The first doubling stage comprises three elements 1A, 3A and 5A similar respectively to elements 1, 3 and 5 of Fig. 3. The input waves are applied through a cathode follower valve 13 having its anode connected directly to the terminal 2 and its cathode connected to terminal 4 through a resistance 14. The control grid of the valve 1A is connected directly to the cathode of the valve 13. The control grid of this valve is connected to ground through a high resistance 15, and the input waves are applied to terminals 16 and 17, the former of which is connected to the control grid, the latter being connected to ground. This cathode follower stage provides in well known manner the desired low impedance input circuit for the doubling valve 1A. The resistance 14 should preferably be chosen so that the desired bias of approximately $E/2$ is obtained on the control grid of the valve 1A, or suitable auxiliary biasing arrangements (not shown) should be provided in any known way. The input waves could, for example, be derived from the valve 1 of Fig. 3 by connecting terminal 11 to terminal 16.

The second doubling stage of Fig. 4 comprises a set of elements 1B, 3B, 5B, 11B and 12B similar to the same numbered elements of Fig. 3. The control grid of the valve 1B is connected directly to the anode of the valve 1A, thus obtaining the proper bias automatically, since as already explained, the anode potential at the minimum point M is approximately equal to $E/2$.

It will be evident that any number of frequency doubling stages could be coupled together and to the source of signals by any of the cou-

pling arrangements which have been described with reference to Figs. 3 and 4.

It may be added that if the input signal voltage is large, so that some distortion is unavoidable as a result of frequency doubling, it is preferable to use large values of R_1 and R_2 , since there will then be less grid current and a smaller loading of the input circuit. The sloping portions of the curves of Fig. 2 are then straighter, since for the negative slope the negative feedback introduced by R_2 is greater, while for the positive slope the voltage across the valve, which varies in a non-linear fashion will be a small proportion only of the applied high tension voltage.

When, however, the input signal voltage is small, and it is desired to avoid distortion as a result of doubling, the range of the parabolic portions of the curves of Fig. 2 may be extended by making R_1 and R_2 rather smaller. This provides less negative feedback and increases the effectiveness of the curvature of the grid-current characteristic of the valve.

The advantages of the circuit according to the invention may be briefly listed below:

1. Since there are no filters or tuned circuits the circuit will operate as a frequency doubler over a wide range of frequencies.

2. If the input amplitude is small, and if the bias of the doubling valve is correctly chosen, the output will consist substantially only of the double frequency waves without other multiple frequencies of appreciable amplitude.

3. The circuit will produce a train of positive output pulses in response to a train of positive or negative input pulses, and if the input pulses are of large amplitude, the output pulses will have substantially the same amplitude. It is not necessary that the adjustment of the bias should be very accurate for this application of the circuit.

4. The circuit may be used as an ordinary amplifier with a gain ratio of approximately unity, and by a simple change of grid bias the phase of the output waves may be changed by 180° without appreciably affecting the amplitude.

What is claimed is:

1. An electric wave translating circuit for frequency doubling comprising a thermionic valve having an anode, a cathode, a control electrode, an anode resistance, a cathode negative feedback resistance, means for applying a signal voltage to the said control electrode, and means for deriving an output voltage from the said anode, in said anode and feedback resistances being of the same value and large compared to the interelectrode resistance between the cathode and grid such that the curve of instantaneous anode voltage versus instantaneous control electrode voltage has a substantially constant negative slope over the lower half of the working range, and a substantially constant positive slope over the remainder of the working range.

2. A frequency doubling circuit according to claim 1 comprising means for biasing the said control electrode close to the potential of said cathode such that when the applied signal voltage is zero the anode voltage is a minimum.

3. A circuit according to claim 1 in which the signal voltage is derived from a low impedance source.

4. A circuit according to claim 1 in which the signal voltage is applied to the control electrode through a transformer having a low impedance secondary winding.

5. A circuit according to claim 1 in which the signal voltage is applied to the control electrode through a cathode follower amplifying stage.
